LIQUID DISPENSING CAP FOR A BOTTLE OR THE LIKE

Norman A. Greene, New Rochelle, N.Y.

Application June 23, 1958, Serial No. 51,468

Term of patent 14 years

(Cl. D2—3)

Fig. 1 is a side elevational view of a liquid dispensing cap for a bottle or the like showing my new design, with a portion of the upright pipe broken away;

Fig. 2 is a side elevational view thereof in depressed position and with a portion of the spout and upright pipe broken away for convenience of illustration;

Fig. 3 is a side elevational view taken from the right of Fig. 1, with a portion broken away at the top, and with the spout element and a portion of the upright pipe omitted for illustrative purposes only; and

Fig. 4 is a bottom plan view of the liquid dispensing cap for a bottle or the like.

The dominant features of the design reside in the portions shown in full lines.

I claim:

The ornamental design for a liquid dispensing cap for a bottle or the like, substantially as shown and described.
